FIG. 1

FIG. 2.

A. J. Todd, Inventor
Chas Williamson By clerk

UNITED STATES PATENT OFFICE

90,930

DESIGN FOR A SPRING CLIP

Augustine J. Todd, Washington, D. C.

Application August 2, 1933. Serial No. 48,919

Term of patent 3½ years

To all whom it may concern:

Be it known that I, AUGUSTINE J. TODD, a resident of Washington, District of Columbia, and a citizen of the United States, have invented a new, original, and ornamental Design for Spring Clips, of which the following is a specification, reference being had to the accompanying drawing, forming a part thereof.

In the drawing:

Fig. 1 is a side view of a spring clip showing my new design;

Fig. 2 is an end view thereof.

My design comprises an opposing pair of jaw

members which are of thin material and in side view have the contour of a bird with extensions from the back of the bird that are or suggest out-spread wings, there being one at each side. It will thus be seen that the bird-like appearance is the dominating characteristic of my new design as a part of the clip-forming members.

I claim:

The ornamental design for a spring clip as shown and described.

In testimony whereof I hereunto affix my signature.

AUGUSTINE J. TODD.
